JAMES C. THOM, OF CHICAGO, ILLINOIS, ASSIGNOR TO COMBINATION MACHINE COMPANY, OF NEW YORK, N. Y., A CORPORATION OF DELAWARE.

MECHANISM FOR APPLYING BOX COVERS.

Application filed January 26, 1921. Serial No. 439,974.

To all whom it may concern:

Be it known that I, JAMES C. THOM, a citizen of the United States, and resident of Chicago, in the county of Cook and State of Illinois, have invented certain new and useful Improvements in Mechanism for Applying Box Covers, of which the following is a specification.

The invention relates to mechanism for automatically applying covers to a succession of boxes and includes, besides the mechanism for actually applying the covers, mechanism for properly feeding and arranging the covers and for feeding the successive boxes to the point of cover application and means for removing the covered boxes from the application point and disposing of them in a desirable way.

The general object of the invention is to provide related mechanisms for the purposes mentioned which are entirely automatic, and which have high out-put capacity and are simple and durable in structure.

More particularly stated the objects are to provide means for feeding and arranging box covers supplied in any suitable way, for example directly from the cover making machine, discarding superfluous covers and covers which are in undesirable positions and rehandling these discarded covers, bringing the covers into initial relation with the boxes, which are well exemplified by such commodity boxes as round, shallow snuff boxes, which are filled before being moved to the cover applying position, applying the covers automatically, advancing the covered boxes in suitable arrangement, and separating suitable groups of boxes for convenience in packing. The characteristics and advantages of the invention will be best understood after considering the physical embodiment shown in the accompanying drawings and described hereafter; and after considering this embodiment it will be evident to skilled persons that many changes may be made in details as well as in combinations and sub-combinations of parts, also that certain parts or sub-combinations of the entire invention are useful in themselves apart from others; and I contemplate the employment of any structures which are

properly within the scope of the appended claims.

In the accompanying drawings:

Fig. 1 is a view mainly in side elevation, 55 but partly in section, of a machine embodying the invention.

Fig. 2 is a top plan of the cover feeding, discarding and arranging mechanism;

Fig. 3 is an enlarged vertical section on 60 the line 3—3, Fig. 1.

Fig. 4 is an enlarged sectional detail on the line 4—4, Fig. 2.

Fig. 5 is an enlarged view mainly in elevation and partly in section, of the cover 65 applying mechanism.

Fig. 6 is a top plan, enlarged, of that part of the mechanism included between the points 6—6, Fig. 1.

Fig. 7 is a side elevation, enlarged, of the 70 package group separating mechanism.

Fig. 8 is an enlarged transverse section of the same.

Fig. 9 is an enlarged detail of the means for initially receiving the covers and supply- 75 ing them to the initial feed belt.

Fig. 10 is an elevational detail of the cover conveying channel.

The machine is specially well adapted to apply covers to such boxes as the round, 80 shallow, or short cylindrical snuff boxes B, best shown in Fig. 5, the cylindrical bodies of which are provided with bottoms A by mechanism with which this invention is not concerned. The bodies B are usually of 85 paste board and the bottoms A are usually of paste board or fibre. These boxes are filled with the desired commodity, such as snuff, by filling mechanism which is also apart from the present invention, and it is desired 90 to automatically apply covers C to the boxes. These covers are preferably of tin stamped or die pressed into the form best shown in Fig. 4, in which one of the covers is shown in inverted position. Each of the covers 95 consists of a round body portion or top 10 and a shallow annular wall or flange 11. The invention is not restricted to handling boxes and covers of the identical character and shape described and the materials may 100 also be varied. The particular example given is one which shows the adaptation of

the present machine to existing forms of containers and covers which are very desirable and efficiently handled by a machine of my invention with great economy over cover applying methods and devices heretofore employed.

My invention comprises in the present embodiment mechanism designated in general by reference character D, for moving a succession of filled boxes B to cover applying mechanism E; mechanism F for initially receiving, conveying, arranging, discarding and selecting covers C and mechanism G for removing and conveniently arranging in suitable groups the covered boxes.

The mechanisms D, E and G are desirably grouped as shown in Fig. 1, in which supports 12 carry longitudinal frame members 13 and 14. Uprights 12 provide bearing supports for shafts 15, 16, on which are mounted, between the supports, sprockets 17 (see Figs. 1 and 6). A chain 18 runs on these sprockets and, at intervals box supports 19 are connected to certain of the chain blocks (see also Fig. 5). Each of these box supports or carriers comprises a base 20, a rear flange 21 having a curved or arc shaped box engaging face 22, and a front flange 23 having a diagonal box directing face 24. The base 20 also has a central downwardly directed flange 25 secured to a chain block, or to certain of the chain rivets by plates 26^a and screws 27^a. The flanges 21 and 23 with their faces 22 and 24 provide openings into which box bodies may be inserted laterally, one into each of the carriers 19, and when so inserted the body is engaged by the curved front face 22 of the rear flange 21 and advanced to the discharge point of the chain. After being placed in the carrier the boxes are further supported and guided by L-shaped guide rails 26 (Fig. 6) having bottom flanges 27 underlying the sides of the box bottoms which project beyond the carriers and side flanges 28 which are spaced apart slightly farther than the diameter of the boxes, these angle plates forming a channel through which the boxes are conveyed by the carriers.

After filling in a separate filling machine, or by hand operations, the filled boxes B are placed on the upper stretch 28^a, (Figs. 1 and 6) of a conveyor-belt which runs in a direction transverse the movement of conveyor chain 18. This belt is carried on suitable pulleys at its ends and is suitably driven in any convenient manner, the pulley supports and driving means being omitted in the drawing. Conveniently the upper stretch 28^a of the belt may be supported by a shelf or table 30 and the lower stretch 31 of the belt may be supported by a shelf 32. At a suitable point adjacent to the cover applying mechanism E a short con-

veyor belt 33 is arranged parallel to chain 18 and with one end supported by a pulley 34 so that the receiving end of this belt lies under the edge of belt 28^a. The shaft of pulley 34 is supported by frame members 35. The other end of belt 33 is carried by a pulley 36, whose shaft is supported in bearings in uprights 37 resting on frame members 13. A guide rail 40 is arranged above the upper stretch of belt 33 near one edge thereof and another guide rail 41 is arranged above the other edge of the belt. Rail 40 has an angular portion 42 extending above the upper stretch of belt 28^a and the curved portion 43 forming one side of a box channel leading to a discharge point where the boxes are introduced into the carriers 19. Guide rail 41 has a portion 44 extending alongside of belt 28^a and the main stretch of rail 41 terminates at about the point 45 forming the other limit of the discharge opening of the channel defined by guides 40 and 41. The filled boxes B placed at different points across the surface of belt 28^a are brought by the advance of the belt against angular portion 42 of guide rail 41 and by continued movement of the belt are moved in contact with the angular guide across the belt surface and into the channel formed between rails 40 and 41 and at the entrance of this channel the boxes slide off the edge of belt 28^a onto the surface of belt 33. The boxes are brought into contact in the guide channel and the movement of belt 33 in connection with the curved portion 43 of rail 40 moves the foremost box in the row onto the next approaching carrier 19, the box being easily located on the carrier between the suitably formed faces of flanges 21 and 23, previously described. The boxes now advance a short distance to the point at which the covers are applied. Since the proper arrangement and presentation of covers at the application point is an essential feature of the complete invention, mechanism for these purposes will now be described.

A supply of covers C is maintained in a hopper 50, Fig. 9, and desirably the covers may be supplied to the hopper by a spout 51, which is in the present instance the discharge spout of a cover making machine. In the hopper the covers are brought in contact with the upwardly inclined portion 52 of the initial cover conveying belt 53. The inclination of belt stretch 52 is provided by relative arrangement of pulleys 54 and 55 and the return stretch 56 within the hopper may also be properly directed by a pulley 57. The belt pulleys have their shafts located in suitable bearings supported by suitable frame members, these details being omitted for the sake of simplicity. Adjacent to the pulley 55 a suitable arranging device for the covers is located consisting in

the present example of a cylinder 60 mounted on a shaft 61 and driven in any convenient manner. This cylinder is supplied with suitable means, such as flaps 61 of leather 5 or other suitable material, (or in some cases brush bristles may be provided) and the cylinder is arranged at such a distance from belt stretch 52 that covers which lie flat on the belt are permitted to pass under the 10 cylinder, but covers which are tilted or unduly elevated by lying one upon another, will not pass the cylinder or its flaps and these improperly positioned covers are knocked or kicked back into the hopper for 15 rehandling by belt stretch 52. The cylinder 60 is driven so that its lower portion travels in the direction opposite to that of the adjacent belt, as indicated by the arrow.

Above the upper stretch of belt 53 at a 20 suitable point (Fig. 2) is located a guide rail 65 which co-operates with another guide rail 66, located near one edge of the belt. Rail 66 has a straight portion 67 parallel to the belt edge and a diagonal portion 68. Belt 65 has a portion 69 parallel to a part of rail member 67, these portions of the two rails constituting a short straight guide channel. Rail 65 also has a diagonal portion 70 forming in co-operation 25 with the adjacent part of rail 66 a converging entrance to the channel just mentioned. Rail 65 also has another diagonal portion 71 co-operating with diagonal part 68 of rail 66 and forming a diagonal continuation 30 of the guide channel, which is of a width only slightly greater than the diameter of the covers. Rail 65 has another straight portion 72 and rail 66 has a parallel straight portion 73 forming a channel 35 which is a continuation of the diagonal guide channel and parallel to belt 53 near its edge. An auxiliary belt 75 is arranged with its upper edge parallel to that of belt 53 and close to it. This auxiliary belt is 40 supported by pulleys 76 and 77, suitably supported on any convenient frame members, such as 78. A portion of the upper stretch of the belt 75 underlies the straight channel formed between rail members 72 45 and 73. The belts may be of any suitable material, but desirably in one embodiment of the invention belt 75 may be of canvas for reasons later explained.

The box covers C approach diagonal rail 55 member 70, distributed indiscriminately across the face of the belt, and either side up, but all arranged singly and flatwise upon the belt by the arranging device previously described. The cover edges 60 strike the diagonal guide member 70 and are moved over toward rail member 67 and then pass in single alinement through the straight channel between rail members 69 and 67 and then through the diagonal channel 65 between members 71 and 68 and in this

movement they pass from the main belt 53 to auxiliary belt 75 and proceed thereon to a point 80 where rail 66 is interrupted giving access from one side of belt 75 to a discharge hopper 82. If the cover applying mechanism is stopped for any reason while the supply of covers to belt 53 continues, the cover channels beyond the point 80 will shortly become filled and covers will tend to pile up adjacent to the discharge 75 point and any such surplus accumulation will crowd the covers off of the belt so that they fall into hopper 82 and are conveyed away in any convenient manner, for instance through the chute 83, Fig. 1, to the 80 upper surface of the return stretch 56 of belt 53; and suitable means (not shown) are provided for removal of these returned or discarded covers to hopper 50 for resupply to the upper stretch of the belt. 85

At a point just beyond hopper 82 an enclosure is arranged above belt 75 and an adjacent portion of belt 53, this enclosure comprising a rail member 85 (see also Fig. 4) located along the edge of belt 75, a rail 90 member 86 parallel to member 85 and located some distance inwardly from edge of belt 53 and upper strips 87 and 88. The rail member 86 and the cover strips are carried by transverse strips 89 having angular portions 90 secured to rail member 85. Substantially above the adjacent edges of the two belts is a short rail member 91 forming a division between two channels of which one is between rail 91 and rail 85 above belt 95 75 and the other is between rail 86 and rail 91 above the adjacent portion of belt 53, each of these channels being slightly greater in width than the diameter of the covers. A cover selector consisting in the present case 100 of a brush 95 is located in the enclosure for the purpose of selecting and passing on for use the covers which are arranged in the desired position, in the present case with their open sides up, and rejecting the covers which 105 are arranged in the other position, that is with open side down. This brush comprises a cylindrical body 96 carried by a shaft 97, mounted in bearings 98 carried by any suitable frame members such as 99 and driven 110 in any convenient manner, for instance by a pulley 100 and belt 101. The brush body is supplied with a plurality of clumps of bristles 102 trimmed to cylindrical contour. The brush is driven in the direction of the 115 arrow (Figs. 1 and 4) and is arranged with its bristle periphery close to the upper surface of belt 75 so that each cover brought past the discharge hopper 82 and into the enclosure is engaged by the bristles. When 120 a cover is arranged with its open side down the bristles slide freely over the smooth top surface of the cover without ability to move the cover laterally and the resistance of the cover to lateral motion is also increased by 125 130

the engagement of its wall edge of relatively small area with the canvas surface of the belt. Such covers, therefore, pass straight ahead on belt 75 and between rail members 91 and 85 until they encounter a 5 diagonal guide or rail member 105 which diverts these improperly positioned covers laterally until they fall off the belt and into a discharge hopper 106 which has a chute 107 similar to chute 83 leading to the return stretch 56 of belt 53, or these rejected covers are returned in any other convenient way to the feed hopper 50.

Covers which are arranged in the manner 15 desired for the present purpose approach the brush with their open sides up, as shown in full lines in Fig. 4, and the brush bristles enter the open side of the cover and are engaged against the annular wall 11 at the 20 left as viewed in Fig. 4 and exert a quite positive grip upon this wall of the cover and, therefore, vigorously move these properly positioned covers over upon belt 53, as shown in dotted lines in Fig. 4, where they strike 25 against rail member 86 and are advanced by belt 53 between that rail member and rail member 91 to a point beyond hopper 106 where these covers, now all positioned with the same side up, are diverted back to belt 30 75 by an angularly arranged rail member 110, and in this movement the alinement of the covers may also be preserved by a co-operative angular member 111.

From this point the covers are caused to 35 travel substantially half-way about the periphery of belt pulley 77 and are guided in this movement by curved rail members 120 and 121 which are substantially continuations of rail members 110 and 111 and by a 40 peripheral guide member 122 secured to members 120 and 121 by strips 123. The covers then arrive with open sides down upon a downwardly inclined surface 124 which forms a continuation of guide member 122 45 and fall by gravity into a chute 128 of any convenient construction by which the covers are guided in a single row in edgewise contact, to the applying mechanism at E. Since the chute 128 is of such considerable length, 50 as is often necessary in the proper locations of mechanisms F and E, that the column of covers in the chute would have considerable weight which would interfere with the proper feeding of the covers to the applying 55 mechanism, the chute may have, as shown in Fig. 10, stretches 129 and 130 arranged at a considerable angle to each other, and the number of these angularly arranged portions may be increased as may be necessary to 60 relieve the lower portion of the cover column of weight to any desired extent. The lower portion of the chute is usually curved to approximately horizontal position beyond the point 131.

65 Adjacent to the applying position the

chute may conveniently comprise (Figs. 5 and 6) a top strip 135, a bottom strip 136 and side strips 137, the various strips being secured together by cross pieces 138. The bottom strip 136 terminates at 140 at a point 70

close to the top of the box body B approaching in one of the carriers 19 and the top strip 135 terminates at 141 a short distance back of the termination of strip 136. A cover placing member 145 is pivoted at 146 75

to a bracket 147 secured to a top channel strip 135. This placing member has an angular face 150 opposing the advancing edge of the cover as it emerges from the ends of channel strips 135 and 136. Member 145 is 80

of suitable weight, or is suitably weighted, or it may be pulled down with spring pressure, so that the foremost edge of the cover is tilted down and its flange or side wall is substantially hooked over the advancing upper edge of the adjacent box body B. The further movement of the body then draws the cover forward along with it and placing member 145 is raised sufficiently to permit the cover to pass below it and at the same 85

time presses the cover approximately into position on the box. As the box passes away the angular face 150 drops somewhat and depresses the forward edge of the next advancing cover until its wall or flange lies 90

below the end 140 of lower channel member 136 in the path of the next advancing box. In this way the boxes, advanced in continuous 95

series as previously described are each supplied with a cover and in fact act, descriptively speaking, to each draw its own 100 cover out of the cover channel and these covers are initially located on the boxes by the co-operative action of the placing member 145.

From this point the covers are caused to 105 travel substantially half-way about the periphery of belt pulley 77 and are guided in this movement by curved rail members 120 and 121 which are substantially continuations of rail members 110 and 111 and by a peripheral guide member 122 secured to members 120 and 121 by strips 123. The covers then arrive with open sides down upon a downwardly inclined surface 124 which forms a continuation of guide member 122 and fall by gravity into a chute 128 of any convenient construction by which the covers are guided in a single row in edgewise contact, to the applying mechanism at E. Since the chute 128 is of such considerable length, as is often necessary in the proper locations of mechanisms F and E, that the column of covers in the chute would have considerable weight which would interfere with the proper feeding of the covers to the applying mechanism, the chute may have, as shown in Fig. 10, stretches 129 and 130 arranged at a considerable angle to each other, and the number of these angularly arranged portions may be increased as may be necessary to relieve the lower portion of the cover column of weight to any desired extent. The lower portion of the chute is usually curved to approximately horizontal position beyond the point 131.

Adjacent to the applying position the

chute may conveniently comprise (Figs. 5 and 6) a top strip 135, a bottom strip 136 and side strips 137, the various strips being secured together by cross pieces 138. The bottom strip 136 terminates at 140 at a point 70

close to the top of the box body B approaching in one of the carriers 19 and the top strip 135 terminates at 141 a short distance back of the termination of strip 136. A cover placing member 145 is pivoted at 146 75

to a bracket 147 secured to a top channel strip 135. This placing member has an angular face 150 opposing the advancing edge of the cover as it emerges from the ends of channel strips 135 and 136. Member 145 is 80

of suitable weight, or is suitably weighted, or it may be pulled down with spring pressure, so that the foremost edge of the cover is tilted down and its flange or side wall is substantially hooked over the advancing upper edge of the adjacent box body B. The further movement of the body then draws the cover forward along with it and placing member 145 is raised sufficiently to permit the cover to pass below it and at the same 85

time presses the cover approximately into position on the box. As the box passes away the angular face 150 drops somewhat and depresses the forward edge of the next advancing cover until its wall or flange lies 90

below the end 140 of lower channel member 136 in the path of the next advancing box. In this way the boxes, advanced in continuous 95

series as previously described are each supplied with a cover and in fact act, descriptively speaking, to each draw its own 100 cover out of the cover channel and these covers are initially located on the boxes by the co-operative action of the placing member 145.

ing the next advancing cover in position for application.

The covered boxes are then desirably brought beneath a presser plate 170, which 5 has an upwardly curved end 171 to guide the covers downward and press them firmly upon the boxes. Plate 170 may also be desirably associated with a pressing roll 175, the lower surface of which is accommodated by a slot 10 in plate 170 so that the roll may bear upon the box tops and press them firmly in position, in addition to the pressing action afforded by plate 170. Conveniently the presser plate and the pressing roll may be 15 associated in the following way: An arm 177 is pivoted at 178 in uprights 179. This arm is slotted to receive the roll 175 and the roll is mounted on a shaft 176 having bearings in the sides of the arm. The arm 20 also carries vertical posts or struts 172 to the lower ends of which the presser plate 170 is connected. In this way the roll and the presser plate are flexibly or pivotally mounted at the point 178. A weight 180 may be 25 provided to increase the pressing effect of the plate and roll and adjustable stops, such as screws 173 may be provided, these being mounted in a transverse extension of the presser plate and arranged to bear upon a 30 suitable frame member, such as the upper edge of the vertical flanges 28 of guide rails 26, this portion of the guide rail being shown broken away in Fig. 1 for the sake of clearness.

35 The properly covered boxes are now advancing in a spaced row on the carriers 19. It is desirable to shift the boxes so that they will lie in contact in flatwise relation or substantially in a column and then to divide this column into groups of the same number of boxes for convenience in subsequent operations. For these purposes the following mechanism is provided in the present embodiment: Above shaft 16 is a 40 shaft 200 (Fig. 1) and to the rear of these shafts is another shaft 201, these shafts being supported in bearing in suitable frame members. Each of the shafts 16, 200 and 201 has a pair of sprockets 204, spaced apart from each other, the pair of sprockets 204 on shaft 16 being additional to the sprocket 17 previously mentioned and being arranged one at each side of said sprocket. A conveyor chain 206 runs over each set of 45 three sprockets consisting of the sprockets 204 in one vertical plane, thus providing two conveyor chains running one at either side of the rear end of conveyor chain 18. Opposite blocks of chain 206 are provided 50 at regular intervals with prongs 208, the two prongs on opposite blocks of the two chains constituting a pair of fingers, the fingers of successive pairs being spaced apart to accommodate between them one of the 55 covered boxes. As each box is advanced

toward the rear end of chain 18 it is brought between two of the pairs of fingers 208 and is elevated and moved about the axis of shaft 200, the boxes being laterally guided in their vertical movement by a channel consisting of separate strips 210. The upper 70 stretches 212 of the conveyor chains 206 are downwardly inclined. At about the time that the boxes B are brought to vertical position just above shaft 200 the lower edge of 75 each box is placed above parallel, fixed supporting rails 215 which have beveled box engaging surfaces 216. The rails are carried by suitable uprights 217. In the rearward movement of the boxes on rails 215, the 80 fingers 208 fall away from them due to the downward angle of the conveyor chains and the last movement imparted to each box by the fingers brings it into contact with the box last released so that the boxes are formed 85 on the rails 215 in a column or row R and each succeeding box pushes the row forward one box width. The boxes may be removed in this row formation in any suitable way, but more conveniently they are separated 90 into groups of a suitable number. For this purpose movable rails 220 connected by a spacer 221 are arranged below and between the inner edges of rails 215 and normally the upper edges of rails 220 are out of contact 95 with the edges of the boxes, as shown clearly in Fig. 8. The bottoms of rails 220 and their spacer rest on cam rollers 222 having cam projections 223. The cam rolls have end flanges 224 to prevent lateral displacement of rails 220, which may be identified as "separating" or "group spacing" devices. Rolls 222 are carried by shafts 226 connected by sprockets and a chain 227 and one of these shafts may be driven by a chain 100 228 from shaft 16. Spacer 221 has a downwardly extending lug 230 provided with a roller 231 engaged by a shifting fork 232 carried by an arm 233 pivotally mounted at 105 234 and this arm or another connected arm 110 235 is connected by a link 236 with a crank 237 on shaft 16. By the chain connections described shafts 226 and their rolls 222 are rotated in properly timed relation to the travel of conveyor chains 206. At each rotation of the cam rolls their cam extensions 223 elevate the shifting or separating frame and the upward movement of this frame elevates as many boxes of the row R as lie 115 over it at the time, this number being always the same owing to the uniformity of motion of the conveyor chains and the shifting frame. At about the same moment that the shifting frame is elevated by the cams to raise a group K of boxes off of rails 215, 120 the shafting frame is moved back by link 236, and the group is moved back correspondingly and finally set down by the action of the cams upon rails 215. The shifting frame is then moved back again in 125 130

lowered position ready to raise and advance another group of boxes the previously advanced groups which still remain upon rails 220 being at the same time again shifted forward and the spacing between them being maintained. This spacing is to enable an attendant to more easily grasp groups of boxes of the proper number for packing or wrapping. Eight boxes are shown in each of the groups K in the present instance, but the number of boxes may be varied by suitably varying the driving connections between the shafts 16 and the roll shafts 226.

To provide for the necessary travel of the shifting frame over the forward cam roll the rails 220 are desirably provided with forward extensions 240 of reduced height, the reduction in height of the upper rail surfaces being sufficient to prevent engagement with boxes in the row R forward of the point 241 at which a shoulder is formed, the upper surfaces of rails 220 being at a higher elevation from this point to the rear ends of the rails. The shoulders 241, therefore, in the present instance determine the point in the row R at which a section of the row will be lifted and moved forward, at each operation of the shifting frame.

Various moving parts of the machine may be driven in different ways, as may be convenient or desirable. It has not been attempted to show driving connections for all of the parts, since these connections may be greatly varied. When the apparatus is used in a place where a line shaft is available, for instance, pulleys may be applied to the line shaft and belt drives arranged from these pulleys to any desired parts of the mechanism. Driving arrangements preferred in certain cases for certain parts of the mechanism are, however, shown in the present embodiment. An electric motor 250 supported on frame members 251, depending from longitudinal frame members 13 may be connected by a belt 252 to a pulley 253 on a shaft 254. This shaft is connected by intermediate reducing gearing 255, 256, 257 and 258 to a shaft 259, which is connected by a belt, or more desirably by a sprocket chain 260 to shaft 200. This shaft drives conveyor chains 206 and through them drives shaft 16 and conveyor chain 18 on which the box supports are mounted. Belt 101 previously mentioned, which drives selector brush 95 may be connected to a pulley 262, and this may be driven from shaft 263 on which pulley 77 of auxiliary belt 75 is mounted, by suitable gear and chain connections, such as chain 265 connecting sprockets 60 on shaft 263 and a shaft 267, and bevel gears 268 connecting shaft 267 and the shaft 269 of pulley 262. Pulley shaft 263, also the shafts of pulleys for driving conveyor belts 28^a and 33, may be driven in any suitable way, for instance from a countershaft or

countershafts (not shown) or by suitable connections to motor 250. Since such driving arrangements may be varied in accordance with well known principles of machine design, they are not here shown in detail.

My complete invention, therefore, comprises means for properly arranging and advancing box covers, selecting covers which are in desired positions and rejecting others, advancing the selected covers in proper sequence to an applying point, advancing boxes to the applying point, applying the covers to the boxes, and insuring their proper location on the boxes, and then advancing the covered boxes and shifting them into endwise column arrangement and then also, desirably separating the row into groups of boxes of a stated number. Evidently many modifications of structure and arrangement may be made in accordance with the principles of the invention as here disclosed.

I claim:

1. Box handling and cover applying mechanism comprising a broad conveyor belt of sufficient width to accommodate more than one box body of a given size arranged widthwise of the belt, a second conveyor belt moving below the first belt and substantially at a right angle thereto, guide means arranged above the belts for diverting boxes advancing in irregular widthwise distribution on the first belt and placing them on the second belt and guiding them thereon in a single row, cover applying means, and means for directing boxes from said second belt to the cover applying means.

2. Box handling and cover applying mechanism, comprising a conveyor belt of substantial width on which filled boxes are placed in indiscriminate lateral positions, a transverse conveyor channel for guiding boxes in a single row arrangement, a second conveyor belt moving beneath said channel and beneath the first named belt, means for diverting boxes from the first named belt to said channel upon said second named belt, a conveyor having spaced box receptacles, said channel being conformed to divert boxes laterally into said receptacles, and cover applying mechanism adjacent to the last-named conveyor.

3. Box handling and cover applying mechanism comprising a conveyor belt on which filled boxes are placed in irregular lateral positions, another conveyor belt transversely arranged, guide means associated with the last named belt to guide boxes in a single row toward a cover applying point, an angular deflector above the belt first mentioned to deflect boxes from it to the second belt and guide means, and means at the cover applying point for applying covers to successive boxes.

4. Box cover applying mechanism com-

- prising a conveyor having spaced box supports, means for inserting a filled box in each support, a cover chute for supplying a row of flanged covers in similar arrangement to a cover applying position over the conveyor, and cover applying means comprising a movable member engaging the covers as they emerge from the channel and serving to tip the forward edge of the foremost cover down and engage its flange with the edge of an advancing box, and additional means for pressing the covers in position.
5. Box cover applying mechanism comprising a conveyor having spaced box supports, means for inserting a filled box in each support, a cover chute for supplying a row of flanged covers in similar arrangement to a cover applying position over the conveyor, and cover applying means comprising a movable member engaging the covers as they emerge from the channel and serving to tip the forward edge of the foremost cover down and engage its flange with the edge of an advancing box, said member also being arranged to additionally press the cover into position, and additional means for pressing the covers in position.
6. Box cover applying mechanism comprising a continuous linear conveyor having spaced box supports, each support having box engaging members arranged to provide a lateral box entrance, means for inserting a box in each support through the lateral entrance, a chute for conveying a series of flanged box covers in similar arrangement under feed pressure to the neighborhood of the conveyor, and a pivoted applying member having an angular face co-operating with the covers to effect initial engagement with the cover of each advancing box.
7. Box cover applying mechanism comprising a continuous linear conveyor having spaced box supports, each support having box engaging members arranged to provide a lateral box entrance, means for inserting a box in each support through the lateral entrance, a chute for conveying a series of flanged box covers in similar arrangement under feed pressure to the neighborhood of the conveyor, and a pivoted applying member having an angular face co-operating with the covers to effect initial engagement with the cover of each advancing box, the applying member also serving to additionally locate the cover on the box in its further advance.
8. Box cover applying mechanism comprising means for advancing a series of filled boxes in edgewise spaced relation, means for applying covers to successive boxes, and means for bringing them together in a row in flatwise contact.
9. Box cover applying mechanism comprising means for advancing a series of filled boxes in a spaced row in substantially horizontal positions, means for applying covers to successive boxes, and means for turning the boxes and bringing them together in a row in substantially vertical positions.
10. Box cover applying mechanism comprising means for covering and advancing a series of boxes in edgewise spaced relation, means for bringing them together in a row in flatwise contact, and means for separating and advancing successive sections of the box row.
11. Box cover applying mechanism comprising means for covering a series of boxes and advancing them in a spaced row in substantially horizontal positions, means for turning the boxes and bringing them together in a row in substantially vertical positions, and means for separating and advancing successive sections of the box rows.
12. Box handling and cover applying mechanism comprising a conveyor having supports on which filled boxes are advanced in substantially horizontal positions in a spaced series, means for applying covers, and another conveyor having means for elevating and turning the boxes to approximately vertical position.
13. Box handling and cover applying mechanism comprising a conveyor having supports on which filled box bodies are advanced in substantially horizontal positions in a spaced series, means for applying covers, another conveyor having means for elevating and turning the boxes to approximately vertical position, and a longitudinal support on which boxes are delivered by said second conveyor.
14. Box handling and cover applying mechanism comprising a conveyor having supports on which boxes are advanced in substantially horizontal positions in a spaced series, means for applying covers, another conveyor having means for elevating and turning the boxes to approximately vertical position, a longitudinal support on which boxes are delivered in a row by said second conveyor, and means for engaging successive sections of the box row and advancing such sections in spaced relation.
15. Box handling and cover applying mechanism comprising a conveyor having spaced box supports on which a series of boxes are advanced in substantially horizontal positions, means for applying covers to boxes advanced on said supports, a second conveyor having box engaging fingers to receive successive boxes delivered by the first conveyor, elevate and turn the boxes to vertical position, and parallel rail sup-

ports on which boxes are advanced in contact in a row as they are delivered by the second conveyor.

16. Box handling and cover applying mechanism comprising a conveyor having spaced box supports on which a series of boxes are advanced in substantially horizontal positions, means for applying covers to boxes advanced on said supports, a second conveyor having box engaging fingers to receive successive boxes delivered by the first conveyor, elevate and turn the boxes to vertical position, parallel rail supports on which boxes are advanced in contact in a row as they are delivered by the second conveyor, a row section separator comprising rails for engaging the lower edges of a section of the box row, and means for alternately raising, advancing, lowering and retracting said separator.

17. Box handling and cover applying mechanism comprising, means for advancing box bodies in a row, means for applying covers to the boxes, a pair of parallel rails for supporting a row of the covered boxes in contact, means for supplying boxes at one end of the rail support, and a row section separator for engaging successive sections of the box row and advancing such sections in spaced relation.

18. Box handling and cover applying mechanism comprising, means for advancing box bodies in a row, means for applying covers to the boxes, a pair of parallel rails for supporting a row of the covered boxes in contact, means for supplying boxes at one end of the rail support, and a row section separator for engaging successive sections of the box row and advancing such sections in spaced relation, said separator comprising connected rails adapted to engage the lower edges of the boxes of such sections, roll supports for the separator, means for driving the rolls, cams for elevating the separator, and means for reciprocating the separator.

19. Box cover applying mechanism comprising means for advancing and covering a series of boxes and cover supply mechanism comprising a first conveyor belt on which covers are advanced in irregular lateral distribution and either side up, a second parallel belt, and means for deflecting covers from the first belt to the second belt and arranging them on the second belt in a single row.

20. Box covering applying mechanism comprising means for advancing and covering a series of boxes and cover supply mechanism comprising a first conveyor belt on which covers are advanced in irregular lateral distribution and either side up, a second parallel belt, and means for deflecting covers from the first belt to the second belt and arranging them on the second belt in a single

row, and means for discharging surplus covers accumulating at a certain point along the second belt.

21. Box cover applying mechanism comprising means for advancing and covering a series of boxes and cover supply mechanism comprising a first conveyor belt on which covers are advanced in irregular lateral distribution and either side up, a second parallel belt, means for deflecting covers from the first belt to the second belt and arranging them on the second belt in a single row, and means for diverting back to the first belt covers which are arranged one side up and permitting the covers which are arranged the other side up to continue on the second belt to a discharge point.

22. Box cover applying mechanism comprising means for advancing and covering a series of boxes and cover supply mechanism comprising a first conveyor belt on which covers are advanced in irregular lateral distribution and either side up, a second parallel belt, means for deflecting covers from the first belt to the second belt and arranging them on the second belt in a single row, and means for engaging covers which are open side up and diverting them to the first belt while permitting covers which are arranged open side down to continue to a discharge point.

23. Box cover applying mechanism comprising means for advancing and covering a series of boxes and cover supply mechanism comprising a first conveyor belt on which covers are advanced in irregular lateral distribution and either side up, a second parallel belt, means for deflecting covers from the first belt to the second belt and arranging them on the second belt in a single row, means for engaging covers which are open side up and diverting them to the first belt while permitting covers which are arranged open side down to continue to a discharge point, and means for conveying diverted covers in a single row to a point of cover application.

24. Box cover applying mechanism comprising means for advancing and covering a series of boxes and cover supply mechanism comprising a belt on which covers are conveyed either side up in a single row, means for selecting covers which are arranged with the same side up and rejecting covers otherwise arranged, and means for conveying selected covers to the point of cover application.

25. In mechanism of the class described, in combination with means for advancing box bodies and applying covers thereto, arranging and feeding mechanism for substantially flat flanged covers comprising means for advancing covers in flatwise positions in substantially a single plane in irregular lateral distribution and either side

up, means for rejecting covers which are out of the normal plane of advance, means for selecting the covers which are one side up and rejecting those which are the other side up, and means for advancing the selected covers in a row in edgewise contact toward cover-applying position.

26. In mechanism of the class described, the combination with means for advancing 10 a series of filled boxes, of a cover channel delivering covers adjacent to the boxes, a movable member having a beveled face for initially applying a cover to each advancing box, and a weighted roller for pressing the 15 covers firmly in position upon the boxes.

27. In mechanism of the class described, the combination with means for advancing a series of filled boxes, of a cover channel delivering covers adjacent to the boxes, a 20 movable member having a beveled face for initially applying a cover to each advancing box, and a pivoted arm and a roll carried by the arm for pressing the covers in position on the boxes.

28. A machine for covering boxes, arranging box parts and arranging the covered boxes, comprising means for advancing box bodies in indiscriminate lateral arrangement, means for arranging such 30 bodies in a row and forwarding them in spaced relation past a covering station, means for forwarding and selecting indiscriminately arranged box tops and advancing tops all with the same side in the same 35 relative position to the covering station, means at the covering station for applying tops to successive boxes, and means for delivering the covered boxes in successive separated groups.

29. A machine for covering boxes, arranging box parts and arranging the covered boxes, comprising means for advancing box bodies in indiscriminate lateral arrangement, means for arranging such 45 bodies in a row and forwarding them in spaced relation past a covering station, means for forwarding and selecting indiscriminately arranged box tops and advancing tops all with the same side in the same 50 relative position to the covering station, means at the covering station for applying tops to successive boxes, and means for delivering the covered boxes in a row and in separated groups.

30. A machine for covering boxes, arranging box parts and arranging the covered boxes, comprising means for advancing box bodies in indiscriminate lateral arrangement, means for arranging such 55 bodies in a row and forwarding them in substantially horizontal position and in spaced relation past a covering station, means for 60 forwarding indiscriminately arranged box tops and selecting tops, and advancing tops

all with the same side in the same relative 65 position to the covering station, means at the covering station for applying tops to successive boxes, and means for delivering the covered boxes in substantially vertical position and in a row in contact. 70

31. A machine for covering boxes, arranging box parts and arranging the covered boxes, comprising means for advancing box bodies in indiscriminate lateral arrangement, means for arranging such 75 bodies in a row and forwarding them in substantially horizontal position and in spaced relation past a covering station, means for forwarding indiscriminately arranged box tops and selecting tops and advancing tops all with the same side in the 80 same relative position to the covering station, means at the covering station for applying tops to successive boxes, and means for delivering the covered boxes in vertical or edgewise position and successive 85 separated groups.

32. A machine for covering boxes, arranging box parts and arranging the covered boxes, comprising means for advancing box bodies in indiscriminate lateral arrangement, means for arranging such 90 bodies in a row and forwarding them in substantially horizontal position and in spaced relation past a covering station, 95 means for forwarding indiscriminately arranged box tops and selecting tops and advancing tops all with the same side in the same relative position to the covering station, means at the covering station for applying tops to successive boxes, and means for delivering the covered boxes in a row 100 and in separate groups with the individual box of each group in contact and in substantially vertical or edgewise position. 105

33. A machine for covering boxes, arranging box parts and arranging the covered boxes, comprising means for forwarding filled boxes in substantially horizontal position and in indiscriminate lateral 110 distribution, means for arranging the filled boxes in line and advancing them in spaced relation past a top applying station, means for advancing flanged box tops in indiscriminate arrangement, means for rejecting superposed or overlapped tops, means for selecting tops arranged with the same side upward and rejecting others, means for advancing the selected tops in a row to the top applying station, means at said station for applying the tops to successive boxes, and means for delivering the covered boxes in spaced groups. 115

Signed at Chicago in the county of Cook and State of Illinois this 22nd day of January A. D. 1921. 125

JAMES C. THOM.
